DESIGN FOR A SOLDERING IRON

Leonard P. Young, Chester, Conn.

Application November 8, 1938, Serial No. 80,956

Term of patent 7 years

To all whom it may concern:

Be it known that Leonard P. Young, a citizen of the United States and resident of Chester, in the county of Middlesex and State of Connecticut, has invented a new, original, and ornamental Design for a Soldering Iron, of which the following is a specification, reference being had to the accompanying drawing, forming part thereof, and in which

The figure is a plan view of a soldering iron showing my design.

The essential features of my design reside in the specific configurations, proportions and arrangement of the respective elements between the handle and the tip of the soldering iron as shown on the drawing.

I claim:

The ornamental design for a soldering iron, as shown and described.

LEONARD P. YOUNG.
